Inventor

C. E. McCANLESS

By

Watson E. Coleman

Attorney.

UNITED STATES PATENT OFFICE.

CHARLES E. McCANLESS, OF BARTLESVILLE, OKLAHOMA.

DESK.

1,192,442.

Specification of Letters Patent. Patented July 25, 1916.

Application filed May 1, 1915. Serial No. 25,261.

To all whom it may concern:

Be it known that I, CHARLES E. McCANLESS, a citizen of the United States, residing at Bartlesville, in the county of Washington 5 and State of Oklahoma, have invented certain new and useful Improvements in Desks, of which the following is a specification, reference being had to the accompanying drawings.

10 This invention relates to desks and more particularly to school desks, the invention having for its primary object to provide a desk of this type wherein the books and other articles are placed within the desk 15 from either end thereof instead of a front opening, as provided in the usual school desk.

It is an additional object of my invention 20 to provide an open-ended school desk having longitudinally sloping or inclined bottom walls extending inwardly from the ends of the desk to its center, whereby the books and other articles are directed, by gravity, toward the central portion of the desk so 25 that they may be readily withdrawn therefrom when desired.

It is a further object of the invention to provide an open-ended desk having a transverse partition wall, and an article supporting rack secured to the front wall of the desk adjacent the ends thereof.

It is also a general object of the invention 30 to improve and simplify the construction of desks of the above type, whereby their convenience and serviceability in practical use is greatly increased without materially enhancing the manufacturing cost thereof.

With the above and other objects in view, 35 my invention consists in the novel features of construction, combination, and arrangement of parts to be hereinafter more fully described, claimed, and illustrated in the accompanying drawing, in which,

Figure 1 is a perspective view of my invention 40 desk; Fig. 2 is a longitudinal section through the same; and Fig. 3 is a section taken on the line 3-3 of Fig. 2.

Referring in detail to the drawing, 5 designates the sloping or inclined top wall 45 of the desk, the forward longitudinal edge of which projects slightly beyond the front wall 6 to provide an overhanging ledge 7. To the rear wall 8 of the desk, the back board 9 is suitably secured, said board ex-

tending the entire length of the desk and 55 projecting above the surface of the top 5, as shown at 10, and also below the bottom wall of the desk. This bottom wall consists of two sections 11 which are inclined inwardly and downwardly from the ends of the desk 60 to the center thereof. The opposite ends of the desk are entirely open, as shown at 12. The desk is also provided with a partition wall 13 which may be arranged centrally 65 within the desk, or at any other desired point between the open ends of the desk. To the inner face of the front wall 6 of the desk, the metal racks 14 are secured, upon which pens, pencils, rubbers and like articles may 70 be placed. These metal racks are located at a sufficient distance inwardly from the open 75 end of the desk to permit of the insertion of the partition wall 13. The desk is, of course, supported at its opposite ends by the usual metal frames or standards 15.

From the foregoing description, taken in connection with the accompanying drawing, the construction and several advantages of the invention will be clearly and fully understood.

Access may be readily had to the interior 80 of the desk from either end thereof so that the books or papers can be removed. The inwardly and forwardly sloping bottom walls of the desk structure tend to overcome 85 the casual outward shifting movement of the books through the open ends of the desk. It will, of course, be understood that, while I have only illustrated one of the metal racks 90 1 in the accompanying drawing, any desired number of these racks may be provided on the front wall of the desk.

The invention, as a whole, is quite simple 95 in its construction and very serviceable and convenient in practical use.

The desk may be made of various sizes and the partition wall 13 constructed of wood or metal, as desired.

While I have shown and described the 100 preferred construction and arrangement of the several features of the device, it is to be understood that the same is susceptible of considerable modification therein, and I, therefore, reserve the privilege of restoring to all such legitimate changes as may be 105 fairly embodied within the spirit and scope of the invention as claimed.

Having thus fully described my invention,

what I desire to claim and secure by Letters Patent is:—

A desk of the character described including supporting end frames, front and back walls connecting the frames and closing the opposite sides of the desk, a top for the desk arranged upon said end frames, and a bottom wall supported by the end frames between said side walls and inclined inwardly and downwardly from one of the end frames,

said frame having an opening therein through which access may be had to the interior of the desk at one end thereof.

In testimony whereof I hereunto affix my signature in the presence of two witnesses. 15

CHARLES E. McCANLESS.

Witnesses:

L. E. HARRIMAN,
B. L. SLACK.
